UNITED STATES PATENT OFFICE.

GEORGE H. FISHER, OF JAMAICA, NEW YORK, ASSIGNOR TO BROWN & SHARPE MFG. CO., OF PROVIDENCE, RHODE ISLAND.

COLLECTOR FOR HAIR CLIPPERS.

Application filed January 26, 1926. Serial No. 83,876.

This invention relates to new and useful improvements in collectors for hair clippers.

An important object of the invention is to overcome the objections attendant upon hair cutting, namely the scattering of loose hair and clippings.

Another object of this invention is to provide a hair collecting attachment for hair clippers, which is attached directly to the clippers, without altering the structure thereof.

Another object of this invention is to provide a hair collecting attachment for hair clippers, which is secured in position upon the clippers by the pivot bolt of the cutting blades.

Another object of this invention is to provide a hair receiver for hair clippers having an open front side adjacent the cutting blades to receive the clipped hair.

A further object of the invention is to provide a device of the character described, which may be readily detached for cleaning the same and for adjusting the mechanism of the hair clippers.

A still further object of the invention is to produce a device of the character described, which is simple and durable, and which may be manufactured and placed upon the market at a reasonable cost.

The foregoing and other objects will be apparent throughout the course of the following description of the drawings, in which;

Figure 1 is a perspective view of the usual hair clippers, with the hair collector secured in position.

Figure 2 is a front elevation of the hair collector,

Figure 3 is a side elevation of the attachment, and

Figure 4 is a bottom plan view of the same.

Referring more in detail to the drawings, A designates generally the usual form of hair clippers having cutter blades 5 and a screw threaded bolt 6 for holding the parts thereof in adjusted position. B designates generally the hair collecting attachment, which is substantially U-shaped.

The hair collector is provided with a top wall 7 and depending end walls 8, the top

wall having a depression 9 therein to strengthen the same. The top wall 7 is formed with an attaching ear 10 having an aperture 11 therein adapted to receive the bolt 6 to secure the same to the clippers.

In operation, the collector is secured to the top of the clippers by the attaching ear 10 through the medium of the screw threaded bolt 6, the lower parts of the end walls being adapted to rest upon the cutter plates which form the bottom wall of the collector.

It will now be seen that the attached device affords a collector which has an open mouth that lies vertically and faces upwardly in use, whereby the clipped hair will fall within the collector, and from which it may be readily removed by gravity upon movement of the collector to direct the mouth thereof downwardly.

Having thus described my invention what I claim as new and desire to secure by Letters Patent is:—

1. In combination with a hair clipper, a hair receiver of substantially U-shape, having top and end walls, the bottom of the receiver overlying and being closed by the cutting blades of the clippers.

2. In combination with hair clippers having a pivot bolt for the cutter blades thereof, including a member having a part disposed over and substantially parallel to the cutter blades of the clippers, means carried by said part and formed to engage the pivot bolt of the cutter blades to secure the member to the clippers, and parts carried by the first named part and arranged to lie close to the ends of the cutters whereby to form a receptacle constituted by the said member and the cutters.

3. In combination with hair clippers having a pivot bolt for the cutting blades thereof, a hair collector having a top and depending end walls, and an attaching ear formed integral with and disposed in a plane substantially parallel with said top wall whereby to secure the same in position upon the clippers.

4. In combination with a hair clipper, having a pivot bolt for the cutting blades, a hair receiver having top and end walls, an attaching ear formed on the top wall and en-

gageable by said bolt, the bottom of the receiver overlying and being closed by the cutting blades of the clippers.

5. In combination with a hair clipper, having a pivot bolt for the cutting blades thereof, a hair receiver having a top and depending end walls carried by the top and supported on the cutter blades, and an at-

taching ear having an opening therein engageable by said pivot bolt to secure the same in position upon the clippers, the bottom of the receiver being closed by the cutting blades.

In testimony whereof I have signed my name to this specification.

GEORGE H. FISHER.
